HEATER

Glenn F. Shaver, Graettinger, Iowa

Application July 27, 1949, Serial No. 107,007

5 Claims. (Cl. 126—367)

1

The principal object of this invention is to provide a heater for burning wood, coal, corn-cobs or the like that has an unobstructed air intake channel into the fire chamber and a baffle plate arranged therein to direct the air toward the center of the heater into the fire and thereby increasing the intensity of the fire.

A further object of this invention is to provide an efficient heater for burning wood, coal, corncobs or the like that can be used either as a space heater or as a water tank heater when partially submerged.

A still further object of this invention is to provide a heater for burning wood, corncobs or the like that is economical in manufacture, efficient in operation and durable in use.

These and other objects will be apparent to those skilled in the art.

My invention consists in the construction, arrangement, and combination of the various parts of the device, whereby the objects contemplated are attained as hereinafter more fully set forth, pointed out in my claims, and illustrated in the accompanying drawings, in which:

Fig. 1 is a perspective view of this device ready for use.

Fig. 2 is a top view of this device with a cut away portion to more fully illustrate its construction, and

Fig. 3 is a cross-sectional view of this device taken on the line 3—3 of Fig. 2 with the horizontal intermittent line indicating a water level when this device is partially submerged in a water tank or like.

Heaters are not new and have been used for many years with various means adapted for providing and creating drafts to increase their efficiency. In my invention I was motivated by a need for increasing the intensity of the fire in heaters used in watering tanks for livestock. In this situation the heater is partially submerged in an open top water tank and obviously the hotter the fire is, the more efficient the heater will function. This can be accomplished by directing a draft at the bottom and center of the fire which I have done in my invention that I will now describe.

Referring to the drawings I have used the numeral 10 to designate a cylindrical housing, having a closed bottom and an open top, which serves as the firebox. The numeral 11 designates a horizontal elongated substantially rectangular combustion chamber having a flat top and flat bottom, is closed at its outer end and communicates at its other end with the side of the housing 10 near the bottom thereof, as shown in Fig. 3. The numeral 12 designates a vertical vent pipe that has its bottom portion in communication with the top of the chamber 11 near its outer end and its top end in communication with the atmosphere. The numeral 13 designates an elongated convex partition member that is arranged within the housing 10 and has its longitudinal edges vertically secured to the inside surface of the housing directly above the point where the chamber 11 communicates with the housing.

2

The top edge of this partition is flush with the top edge of the housing and the bottom edge terminates slightly above the communicating point of the housing and chamber, as shown in Fig. 3. Thus arranged, the partition serves to provide an unobstructed air channel into the firebox. As shown in Fig. 3 the partition is constructed so that the width of the air channel is somewhat greater at the top than at the bottom, and this was provided so that air drawn into the fire will be directed against the baffle plate 14 that is positioned at the bottom of the air channel. This baffle plate 14 is secured to the inside of the housing 10, as shown in Fig. 3, and extends inwardly and downwardly therefrom. By positioning this baffle plate at an angle as described it serves to direct the air intake toward the bottom and center of the firebox and thereby greatly increases the intensity of the fire.

The numeral 15 designates a circular flat lid provided with a downwardly extending flange member about the periphery thereof. The lid 15 is hinged to the partition 13 by any suitable means that will allow it to be raised to a ninety degree opening, or more, at times. The numeral 16 designates a hole provided in the lid and the numeral 17 designates a pear-shaped movable cover member, pivotally secured at its smaller end to the top surface of the lid 15 so that the larger end of the cover can be manually laterally moved to adjustably close or expose the hole 16 when desired. The numeral 18 designates support members suitably arranged at a plurality of points on the bottom of this device and designed for use in securing this device to any supporting surface.

In using this device a fire is started by any suitable means in the bottom of the housing. For this purpose coal, wood, corncobs or the like may be used. In farm areas it is found that corncobs make good fuel, and thereby not only provide a source of economical heat but also provide a means for disposing of the cobs. After the fire is started the amount of draft through the air channel is controlled by the movable cover on the lid and when the draft is opened, the baffle plate at the bottom of the air channel will direct that air directly into the bottom of the fire which greatly increases the efficiency of this heater.

The lid 15 is preferably hinged to the housing to guard against its becoming lost and more particularly to keep it from falling off where it could become bent or broken requiring replacement in the latter and decreasing the efficiency of the draft control means in the former. The cover 17, being the draft control means, is arranged as described so that when the lid is opened for refueling the greatest maximum area of the housing possible is available for filling with the fuel used.

Some changes may be made in the construction and arrangement of my heater without departing from the real spirit and purpose of my invention, and it is my intention to cover by my claims, any modified forms of structure or use of mechanical

equivalents which may be reasonably included within their scope.

I claim:

1. In a device of the class described, a cylindrical housing member open at its top, a horizontal enclosed chamber communicating at one end with the inside of said housing near the bottom thereof and closed at its other end, a vent pipe communicating at one end with the free end of said chamber and at its other end with the atmosphere, an elongated convex partition member having its longitudinal edges vertically secured to the inside of said housing above the point where said chamber communicates with said housing; said partition member creating an air flow chamber within said housing from the top edge thereon to a point just above the point where said first mentioned chamber communicates with said housing and said air flow chamber being wider at its top portion than at its lower portion, a baffle plate secured to the inner side surface of said chamber at a point below and adjacent said channel and extending downwardly and inwardly therefrom whereby air is deflected toward the center and bottom of said housing, a hinged lid member arranged on the top of said housing; said hinge secured to said partition member, a hole provided in said lid over said channel portion, and a laterally manually movable cover pivotally secured to said lid so as to be capable of adjustably exposing and closing said hole.

2. In a device of the class described, a cylindrical housing member open at its top, a horizontal enclosed chamber communicating at one end with the inside of said housing near the bottom thereof and closed at its other end, a vent pipe communicating at one end with the free end of said chamber and at its other end with the atmosphere, an elongated convex partition member having its longitudinal edges vertically secured to the inside of said housing above the point where said chamber communicates with said housing; said partition member creating an air flow chamber within said housing from the top edge thereon to a point just above the point where said first mentioned chamber communicates with said housing and said air flow chamber being wider at its top portion than at its lower portion, a baffle plate secured to the inner side surface of said chamber at a point below and adjacent said channel and extending downwardly and inwardly therefrom whereby air is deflected toward the center and bottom of said housing, a lid member arranged on the top of said housing, a hole provided in said lid over said channel portion, and a laterally manually movable cover pivotally secured to said lid so as to be capable of adjustably exposing and closing said hole.

3. In a device of the class described, a cylindrical housing member open at its top, a horizontal enclosed chamber communicating at one end with the inside of said housing near the bottom thereof and closed at its other end; said chamber having a flat top and flat bottom, a vent pipe communicating at one end with the free end of said chamber and at its other end with the atmosphere, an elongated convex partition member having its longitudinal edges vertically secured to the inside of said housing above the point where said chamber communicates with said housing; said partition member creating an air flow chamber within said housing from the top edge thereon to a point just above the point where said first mentioned chamber communicates with said housing and

said air flow chamber being wider at its top portion than at its lower portion, a baffle plate secured to the inner side surface of said chamber at a point below and adjacent said channel and extending downwardly and inwardly therefrom whereby air is deflected toward the center and bottom of said housing, a lid member arranged on the top of said housing, a hole provided in said lid over said channel portion, and a laterally manually movable cover pivotally secured to said lid so as to be capable of adjustably exposing and closing said hole.

4. In a heater, an open top firebox, an enclosed combustion chamber communicating at one end with the inside of said firebox near the bottom thereof and closed at its other end, a vent pipe communicating at one end with said combustion chamber and at its other end with the atmosphere, a vertical partition provided within said firebox terminating at its bottom end at a point above and closely adjacent the communicating point between said firebox and said combustion chamber, a baffle plate secured to the inside of said firebox at a point below and adjacent the bottom of said vertical partition and extending downwardly and inwardly therefrom whereby air passing downwardly through said partition is deflected toward the bottom of said firebox for the purpose of increasing the intensity of any fire therein, and means for adjustably controlling the flow of air through said vertical partition.

5. In a device of the class described, a cylindrical housing member open at its top, a horizontal enclosed chamber communicating at one end with the inside of said housing near the bottom thereof and closed at its other end, a vent pipe communicating at one end with the free end of said chamber and at its other end with the atmosphere, and elongated convex partition member having its longitudinal edges vertically secured to the inside of said housing, said partition extending from the top of said housing toward but not to the bottom thereof and terminating just above the point of communication between said housing and said chamber to form an air flow chamber within said housing, a fixed baffle plate secured to the inside of said housing and extending inwardly and downwardly therefrom intermediate the bottom of said partition and the communicating point of said housing and said chamber whereby air is deflected toward the center and bottom of said housing, a lid arranged on said housing, and a means to adjustably expose to the atmosphere the upper portion of said partition.
